ELECTRIC SWITCH

William Lawrence Butler, Schenectady, N. Y.,
assignor to General Electric Company, a corporation of New York

Application March 25, 1939, Serial No. 264,157

14 Claims. (Cl. 200—153)

My invention relates to electric switches, more particularly to limit switches having an element operable to the circuit opening and circuit closing positions, and has for an object the provision of a simple, reliable and improved switch of this character.

In carrying my invention into effect in one form thereof, I have provided a cam-operated limit switch enclosed in a suitable casing. A demountable bearing plate is secured to the casing for supporting the entire movable operating and switching structure, thereby permitting easy assembly and removal of these parts as a unit from the casing. A fixed switching element is supported in the casing, and a cooperating movable switching element is pivotally mounted on the bearing plate. For operating the movable switching element in accordance with the movement of an actuating handle positioned outside the casing, a cam means is provided, and provision for limited over-travel of this means is made. In addition, a simple spring arrangement is provided for biasing the operating means to and for return to an initial position, while serving simultaneously to bias the movable switching element to its initial position. A contact structure is carried by the movable switching element and is especially adapted for a wiping engagement with the contacts of the fixed switching element.

For a further and more complete understanding of my invention, reference should now be had to the following specification and to the accompanying drawing of which Fig. 1 is an elevational view of a casing embodying the switch of my invention and showing various positions of the exteriorly disposed actuating handle; Fig. 2 is a sectional view taken along the lines 2—2 of Fig. 1 looking in the direction of the arrows; Fig. 3 is an elevational view similar to Fig. 1 with the bearing plate and the cover plate of the casing removed and showing the switch in the normal position; Fig. 4 is an elevational view similar to Fig. 3 but showing the switch in the operated position; and Fig. 5 is an exploded view in perspective of the details of Figs. 1 to 4. Referring now to the drawing, I have shown my invention in one form as a limit switch having a suitable enclosing casing 10 provided at the front thereof with a cover plate 11 secured by the screws 12. The casing 10 is provided with a conduit receiving opening 13 through which the controlled connections (not shown) may enter the casing. Preferably, the cover plate 11 is mounted on the front side of the casing 10 so

that the switch may be wired from the front side.

Actuating means for the switch, shown as the rotatably mounted actuating shaft 14, extends through the front side of the casing. The actuating shaft 14 is mounted for rotation in the rear wall of the casing 10 and is journaled in a demountable bearing plate 15 arranged in the front side of the casing. The screws 16 serve to secure the bearing plate 15 on to the casing 10, the front side of the bearing plate 15 being flush with the front surface of the cover plate 11 so that a continuous smooth surface is presented at the front of the casing.

On the extension of the shaft 14, which projects through the front side of the casing, is mounted a switch-operating lever arm 17. Suitable fastening means for the lever arm 17 is provided at its secured end, such as a bifurcated portion 18 and the nut and bolt 19. On the free end of the lever arm 17, a conventional roller 20 is mounted for co-operation with the machine part to be controlled. The normal position of the lever arm is shown in full lines in Fig. 1, its operated position being shown in dotted lines. Simply by loosening the nut and bolt 19, the lever arm 17 may readily be adjusted to any desired normal position by rotation on the shaft 14.

The switch is provided with a fixed switching element which co-operates with a movable switching element in a manner explained more fully hereinafter to perform the switching function. For example, the fixed switching element comprises a pair of contacts 21 to be bridged by the movable switching element in the normal position and a pair of contacts 22 to be bridged by the movable switching element in the operated position, suitably secured on an insulated support 23 fastened on the back wall of the casing 10 by the screws 24. In this manner, the casing serves as a support for the fixed element of the switch, i. e., the normally closed contacts 21 and the normally open contacts 22. The movable switching element comprises, for example, the bridging contacts 25 and 26 which are disposed adjacent the pairs of fixed contacts 21 and 22 for arcuate movement therebetween, the bridging contact 25 coacting and normally in engagement with the fixed contacts 21, and the bridging contacts 26 coacting and normally in disengagement with the fixed contacts 22.

The switch is also provided with a pivoted operating element which serves as a main support and operating means for the movable switching

element. Preferably, this operating element comprises a pivotally mounted operating arm 27 which may be made of a suitable insulating material, such as a plasticizable phenolic condensation product, the operating arm 27 being pivoted on a pin 28 mounted on the bearing plate 15. The operating element 27 has an extending portion, for example, the post 29, which extends transversely of and substantially perpendicular to the line of movement of the movable contacts 25 and 26. As shown, the post 29 comprises an insert molded into the member 27 or it may be a projection formed integrally with the member 27. Confining means are provided 10 on the post 29 to hold a helical spring 30 thereon, this means being here illustrated as a collar 31 on the lower end of the post and the main supporting element 27. The helical spring encircles the post 29 and is held under compression 15 between the confining means, auxiliary supporting means for the movable contacts being interposed between the collar 31 and the adjacent end 20 of the spring 30 as described hereinbelow.

The auxiliary supporting means for the movable contacts is carried by the post 29 to afford means whereby a good wiping engagement of these contacts with their respective fixed contacts is secured. This supporting means comprises the elements 32 and 33, which are identical, 25 each of them carrying one pair of movable contacts thereon. The element 32, for instance, has an upper portion 34 lying on a plane substantially perpendicular to the axial line of the post 29 or the spring 30 and provided with suitable mounting means, such as an open-ended key-hole slot or aperture 35, for receiving the post 29 therein, the portion 34 of the element 32 being disposed between the lower end of the spring 30 and the collar 31. The lower portion 36 of the element 30 32 may have any suitable configuration whereby the movable contacts 25 are supported in spaced relation to the plane of the upper portion 34 for providing a leverage which will serve to rock or roll the upper portion 34 on the collar 31 when 35 the contacts engage and disengage. Preferably, the lower portion 36 of the element 32 lies in a plane transverse to the line of movement of the movable contacts and substantially parallel to the post 29.

50 As seen in Fig. 3, with the switch in its normal position, the contacts 21 and 25 are biased into engagement, the auxiliary support 32 being tilted slightly on the edge of the collar 31. When the contacts 21 and 25 are out of engagement, the upper portion 34 of the support 32 lies flat along, 55 the collar 31. At the moment of engagement, the contact 25 presses against the contact 21, causing the support 32 to tilt and simultaneously slide the contact 25 downwardly across the contact 21, providing a good wiping engagement of these contacts. Upon disengagement, the contact 25 slides upwardly and then away from the contact 21.

60 As seen in Figs. 3 and 4, I have provided the two elements 32 and 33 each supported on the post 29, but facing in opposite directions. Since a single element of this character might be provided to support all of the movable contacts or a pair of posts might be provided, each post supporting a single element, without departing from the spirit and scope of my invention, I do not wish to be limited to the exact contact structure herein described.

65 The operating element 27 referred to above is rotated about its pivot point 28 by a suitable

operating member, preferably a cam 37 secured on a squared portion of the actuating shaft 14. To minimize the friction in the camming relationship between the operating member 37 and the operating arm 27, I provide a roller 38 supported by the operating arm 27 in engagement with the outer edge of the cam 37. Limiting means are provided to determine the extent of angular movement of the cam 37, and this means comprises a stop 39 disposed between a pair of spaced apart projections 40 and 41 on the upper peripheral edge of the cam 37. The stop 39, preferably cast integrally with the bearing plate 15, is shown secured to the upper portion of the bearing plate by means of a screw 42.

70 It will be observed that I have provided spring means for biasing the cam 37 and the operating element 27, respectively, to their normal positions as shown in Fig. 3. The spring means is arranged to be tensioned by the movement of the cam 37 from its normal position to the operated position, shown in Fig. 4, for biasing the operating element 27 and the cam for a quick return from the operated position to the normal position, when the actuating handle 17 is released. A 75 single helical spring 43 comprises the spring means above, and it encircles the inner end of the shaft 14 between the cam 37 and the rear wall of the casing 10. As shown in Figs. 3 and 4, the end of the spring 43 adjacent the cam 37 80 engages a projection 44 thereon for biasing the cam in a clockwise direction, the rotation of the cam in this direction being limited by the stop 39 and the co-operating projection 41 on the cam. The other end of the spring 43 co-operates with 85 a member 45 rotatably mounted on the shaft 14 to bias this member in a counter-clockwise direction, as viewed in dotted lines in Fig. 3.

90 The operating element or arm 27 described above is preferably of U-shape with the pivot 28 at the end of one arm of the U and a pin 46 at the end of the other arm of the U, the post 29 projecting downwardly from an intermediate portion of the U. The member 45, previously described as being biased in a counter-clockwise direction by the spring 43, has a projection 47 which engages the pin 46 on the operating element 27 to bias the operating element 27 in the counter-clockwise direction also. In this manner, the operating element 27 is biased to the 95 normal position shown in Fig. 3 when the contacts 21 and 25 are in engagement.

100 In operation of the switch, the contacts 21 and 25 are normally engaged since the operating arm 27 is biased in a counter-clockwise direction by the spring 43, and the cam 37 is biased in a clockwise direction so that the projection 41 thereon engages the stop 39, the actuating handle 17 being in the upper position shown in full lines in Fig. 1. As the handle 17 is moved downwardly to rotate the shaft 14 in a counter-clockwise direction, the cam 37 is also moved in a counter-clockwise direction against the bias of the spring 43, the spring 43 being further tensioned during this movement. Counter-clockwise rotation of the cam 37 forces the roller 38 and the operating element 27 downwardly causing the operating element to rotate in a clockwise direction around its pivot 28, causing further tensioning of the spring 43. Upon sufficient 105 clockwise rotation of the operating element 27, the contacts 21 and 25 are disengaged with a wiping action, as hereinbefore described, and subsequently the contacts 22 and 26 are caused to engage, also with a wiping action.

It should here be noted that the amount of angular movement of the cam necessary to disengage the contacts 21 and 25 and then engage the contacts 22 and 26 is determined entirely by the shape of the operating edge of the cam 37. The engagement and disengagement of the contacts may be made quite abrupt or slow relative to the angular movement of the cam. I prefer to make the slope of the cam operating sur-

- 10 face away from its center of rotation quite abrupt so that the contacts are operated from the normal position, shown in Fig. 3, to the operated position, shown in Fig. 4, by a relatively small angular movement of the actuating handle 17. 15 The remaining portion of the camming edge, after the abrupt operating slope on the cam periphery, is on the arc of a circle having as its center, the center of rotation of the shaft 14, so that there may be a continuing movement of 20 the actuating handle 17 and the cam 37 in the counter-clockwise direction without further affecting the movement of the operating element 27 in the operated position. In this manner, a 25 desirable amount of over-travel of the cam is provided for, the limit of this over-travel being determined by the engagement of the projection 40 on the cam with the stop 39. However, the operating portion of the cam may be positioned 30 at any point on the periphery of the cam to approach over-travel as desired.

Referring now more specifically to the spring 43, the movement of the operating element 27 from the normal position to the operated position, shown in Fig. 4, serves to further tension the spring 43 since the engaged parts, namely the pin 46, the projection 47 on the member 45, and the end of the spring 43, all move downwardly as the operating element 27 moves to the operated position. Since the spring 43 is tensioned at each 40 end upon movement of the actuating handle 17 from the normal position to the operated position, upon release of the actuating handle 17, the spring tension serves to rotate the cam 37 in the clockwise direction until the roller 38 on the operating element 27 reaches the abrupt slope on the cam. Thereupon, the operating element 27 is permitted to move upwardly under the bias of the spring 43 for disengaging the contacts 22 and 26 reengaging the contacts 21 and 25 in the 50 normal position, shown in Fig. 3.

It should now be apparent that since all of the movable operating parts of the switch are either directly mounted on the demountable bearing plate 15 or supported by elements which are 55 mounted thereon, the removal of the bearing plate from the casing 10 brings with it all of these operating parts. For factory assembly, the actuating handle 17, shaft 14, the spring 43, the cam 37, the stop 42 and the remaining removable 60 elements of the switch may be assembled on the bearing plate 15 and adjusted and tested as an operating unit before mounting in the casing 10.

While I have shown a particular embodiment of my invention, it will be understood, of course, 65 that I do not wish to be limited thereto since many modifications may be made, and I therefore contemplate by the appended claims to cover any such modifications as fall within the true spirit and scope of my invention.

70 What I claim as new and desire to secure by Letters Patent of the United States is:

1. A controller comprising a stationary switch element, a movable switch element cooperating therewith, a member rotatable from a first posi- 75 tion to a second position, a pivoted operating ele-

ment in camming relationship with said member for moving said movable switch element, said operating element moving from a first to a second position in accordance with a predetermined movement of said member, and a single spring 5 simultaneously serving to bias said member and said operating element respectively to said first positions.

2. A controller comprising a stationary switch element, a movable switch element cooperating therewith, a member rotatable from a first position to a second position thereby, a pivoted operating element in camming relationship with said member for moving said movable switch element, said operating element moving from a first to a second position in accordance with a predetermined movement of said member, and a single helical spring simultaneously serving to bias said member and said operating element respectively to said first positions, said spring 20 being further tensioned by movement of said member from said first position toward said second position for returning said member and said operating element to their said respective first positions upon the release of said member. 25

3. A controller comprising a stationary switch element, a movable switch element cooperating therewith, a rotatable actuating shaft, a cam carried by said shaft and rotatable from a first position to a second position thereby, a pivoted 30 operating element operable from a first position to a second position by said cam in accordance with a predetermined movement thereof for moving said movable switch element, a single helical spring serving simultaneously to bias said 35 cam and said operating element respectively to said first positions, said spring being tensioned by movement of said cam from said first position toward said second position for returning said cam and said operating element to their said respective first 40 positions upon the release of said actuating shaft, and means limiting the rotation of said cam for determining said first and said second positions thereof.

4. A controller comprising a stationary switch element, a movable switch element cooperating therewith, a rotatable actuating shaft, a cam carried by said shaft and rotatable from a first position to a second position thereby, a pivoted operating element operable from a first position 50 to a second position by said cam in accordance with a predetermined movement thereof for moving said movable switch element, a single helical spring encircling said shaft and simultaneously serving to bias said cam and said operating element respectively to said first positions, said spring being further tensioned by movement of said cam from said first position toward said second position for returning said cam and said operating element to their said respective first 55 positions upon the release of said actuating shaft, said cam having a predetermined over-travel after operation of said operating element to said second position, and limiting means including a stop and a pair of projections on said cam for 60 determining said first and said second positions of said cam.

5. A controller comprising a casing, a stationary switching element secured in said casing, a demountable bearing plate mounted on a wall of 70 said casing, and operating means for said controller in said casing, said operating means comprising a rotatable actuating shaft journaled in said bearing plate, a member carried by said shaft and rotatable from a first position to a second posi- 75

tion thereby, a pivoted operating element in camming relationship with said member for moving said movable switch element, said operating element moving from a first to a second position in accordance with a predetermined movement of said member, and spring means biasing said member and said operating element respectively to said first positions, said spring means being further tensioned by movement of said member from said first position toward said second position for returning said member and said operating element to their said respective first positions upon the release of said actuating shaft, said bearing plate and said operating means comprising a unitary structure readily removable from said casing without requiring disassembly of said unitary structure.

6. A controller comprising a casing, a stationary switching element secured in said casing, a demountable bearing plate mounted on said casing, and operating means for said controller, said operating means comprising an actuating shaft journaled in said bearing plate and having a first portion extending into the interior of said casing and another portion accessible from the exterior thereof, a cam on said first portion of said shaft for rotation thereby from a first position to a second position, an operating arm in said casing, a pivot for said arm on said bearing plate, a roller on said arm engaging said cam for moving said arm from a first position to a second position in accordance with a predetermined movement of said cam, spring means biasing said arm to said first position, and a movable switching element secured to said arm, said operating means and said bearing plate comprising a unitary structure readily removable from said casing without requiring disassembly of said unitary structure.

40 7. A controller comprising a stationary switch element, a movable switch element cooperating therewith, a rotatable actuating shaft, a cam associated with said shaft and rotatable from a first position to a second position thereby, a pivoted operating element operable from a first position to a second position by said cam in accordance with a predetermined movement thereof for moving said movable switch element, a helical spring encircling said shaft having one end biasing said cam and its other end biasing said operating element respectively to their said first positions, said helical spring being further tensioned by movement of said cam from said first position toward said second position for returning said cam and said operating element to their said respective first positions upon the release of said actuating shaft, and limiting means including a stop and a pair of projections on said cam for engaging said stop to determine said first and said second positions of said cam.

60 8. A controller comprising a rotatable actuating shaft, a member on said shaft and rotatable from a first position to a second position thereby, a pivoted operating element in camming relationship with said member for movement thereby from a first position to a second position, spring means biasing said member and said operating element respectively to their said first positions, and switching means operable by said operating element including a relatively fixed contact and a movable contact for engagement therewith, a main support for said movable contact, said main support being mounted on said operating element and having a portion extending transversely of the line of movement of said movable

contact, a spring, means confining said spring under compression, an auxiliary support for said movable contact having a portion supported by said main support and extending transversely thereof, said portion of said auxiliary support being positioned between an end of said spring and said confining means and held under the bias of said spring, said auxiliary support having a further portion extending transversely of said line of movement of said movable contact for mounting said movable contact to provide a leverage for pivoting or rocking said auxiliary support upon engagement of said contacts, said auxiliary support being loosely mounted on said main support for pivotal movement on said confining means to provide a wiping engagement of said contacts.

9. A controller comprising a rotatable actuating shaft, a member secured to said shaft and rotatable from a first position to a second position thereby, a pivoted operating element in camming relationship with said member for movement thereby from a first position to a second position, spring means biasing said member and said operating element respectively to their said first positions, and switching means operable by said operating element including a relatively fixed contact and a movable contact for engagement therewith, a main support for said movable contact, said main support being mounted on said operating element and having a portion extending transversely of the line of movement of said movable contact, a helical spring encircling said transversely extending portion of said main support, means disposed at each end of said spring confining it under compression, an auxiliary support for said movable contact having a portion normally positioned at substantially right angles to the axial line of said spring and disposed between an end of said spring and said confining means, said auxiliary support having a further portion extending transversely of said line of movement of said movable contact for mounting said movable contact to provide a leverage for rocking or pivoting said auxiliary support upon engagement of said contacts, said auxiliary support being loosely mounted on said main support for pivotal movement on said confining means to provide a wiping engagement of said contacts.

50 10. A controller comprising a rotatable actuating shaft, a member secured to said shaft and rotatable from a first position to a second position thereby, a pivoted operating element in camming relationship with said member for movement thereby from a first position to a second position, spring means biasing said member and said operating element respectively to their said first positions, said spring means being further tensioned by movement of said member from said first position toward said second position for returning said member and said operating element to their said respective first positions upon release of said actuating shaft, and switching means operable by said operating element including a relatively fixed contact and a movable contact for engagement therewith, a main support for said movable contact, said main support being mounted on said operating element and having a portion extending transversely of the line of movement of said movable contact, a helical spring encircling said transversely extending portion of said main support, means disposed at each end of said spring confining it under compression, an auxiliary support for said movable

contact having a portion normally positioned at substantially right angles to the axial line of said spring and disposed between an end of said spring and said confining means, said auxiliary support having a further portion extending transversely of said line of movement of said movable contact for mounting said movable contact to provide a leverage for rocking or pivoting said auxiliary support upon engagement of said contacts, said auxiliary support being loosely mounted on said main support for pivotal movement on said confining means to provide a wiping engagement of said contacts.

11. The combination with a controller having an operating element of switching means for said controller operable by said operating element including a relatively fixed contact and a movable contact for engagement therewith, a main support for said movable contact, said main support being mounted on said operating element and having a portion extending transversely of the line of movement of said movable contact, a spring, means confining said spring under compression, an auxiliary support for said movable contact having a portion supported by said main support and extending transversely thereof, said portion of said auxiliary support being positioned between an end of said spring and said confining means and held under the bias of said spring, said auxiliary support having a further portion extending transversely of said line of movement of said movable contact and associated with said movable contact to provide a leverage for pivoting or rocking said auxiliary support upon engagement of said contacts, said auxiliary support being loosely mounted on said main support for pivotal movement on said confining means to provide a wiping engagement of said contacts.

12. The combination with a controller having an operating element of switching means for said controller operable by said operating element including a relatively fixed contact and a movable contact for engagement therewith, a main support for said movable contact, said main support being mounted on said operating element and having a portion extending transversely of the line of movement of said movable contact, a helical spring encircling said transversely extending portion of said main support, means disposed at

each end of said spring confining it under compression, an auxiliary support for said movable contact having a portion normally positioned at substantially right angles to the axial line of said spring and disposed between an end of said spring and said combining means, said auxiliary support having a further portion extending transversely of said line of movement of said movable contact for mounting said movable contact to provide a leverage for rocking or pivoting said auxiliary support upon engagement of said contacts, said auxiliary support being loosely mounted on said main support for pivotal movement on said confining means to provide a wiping engagement of said contacts.

13. An electric switch comprising a cam, means mounting said cam for rotation about a predetermined axis, an actuating member pivotally mounted for movement about an axis substantially parallel with said first axis but spaced therefrom, a spring operatively associated with said cam and said actuating member respectively for biasing said actuating member about its axis into engagement with said cam and for biasing said cam and said actuating member in opposite directions about their respective axes to predetermined relative first positions, said cam being shaped to turn said actuating member about its axis when said cam is turned from said first position, and circuit control means actuated by movement of said actuating member.

14. An electric switch comprising a cam, a shaft mounting said cam for rotation about a predetermined axis, an actuating member pivotally mounted for movement about an axis substantially parallel with said first axis but spaced therefrom, a spring surrounding said shaft having its ends operatively associated with said cam and said actuating member respectively so as to bias said actuating member about its axis into engagement with said cam and so as to turn said cam and said actuating member in opposite directions about their respective axes to predetermined relative first positions, said cam being shaped to turn said actuating member about its axis when said cam is turned from said first position, and circuit control means actuated by movement of said actuating member.

WILLIAM LAWRENCE BUTLER.
